UNITED STATES PATENT OFFICE

JOHN HAYS HAMMOND, JR., OF GLOUCESTER, MASSACHUSETTS

COMBINATION CIGARETTE CASE AND LIGHTER

Application filed April 30, 1927. Serial No. 187,797.

This invention relates to cigarette devices.

One object of the present invention is to provide a convenient cigarette holder and lighter therefor arranged within a single compact container and including automatic means operable in the natural sequence of extracting a cigarette and resetting the container cover.

One feature of the invention relates to the provision of a pair of hinged covers for the device, one associated with the cigarette holding portion, and the other associated with the lighting portion. According to this feature, friction lighting means are provided, actuated by movement of one of the covers, this movement being initiated upon the closing of the cover associated with the cigarette holding portion. Thus, after one or more cigarettes have been extracted, one cover is released and this automatically releases the other cover, causing the friction lighting means to operate.

Other objects will appear from the following description taken in connection with the accompanying drawings in which

Fig. 1 is a front elevation partly in section of a cigarette container embodying features of the invention, with the storage compartment open;

Fig. 2 is a vertical section taken on the line 2—2 of Fig. 1;

Fig. 3 is a horizontal section taken on the line 3—3 of Fig. 1;

Fig. 4 is a front elevation partly in section with the lighting compartment open; and

Fig. 5 is a top plan view with the lighting compartment open.

Like reference characters denote like parts in the several figures of the drawing.

In the following description and claims, parts, characteristic features and functions will be identified by specific means for convenience of expression, but they are intended to be as generic in their application to similar parts or equivalent construction as the art will permit.

Referring to the drawings, there is shown a casing 10 divided into storage compartment and a lighting compartment and having hinged thereto a lid 11 for the storage com-

partment. The lid 11 tends to be forced into the open position shown in Fig. 1 by springs such as 12, shown two in number, and is provided with a lug 13, at the free end of the lid 11, which engages in the closed position 55 of the cover a spring-pressed latch 14. The latch 14 is positioned on the free end of a leaf spring 15, the other end of which is secured to the inner face of the casing 10. A button 16 extends through an aperture in the wall of the casing and when depressed manually serves to release the lid 11. A pair of strips 17 and 18 are yieldingly held within the casing 10 and its lid 11 respectively in order to maintain in fixed position a plurality of cigarettes, such as 20, 21. There is thus formed a storage compartment 22 for cigarettes.

The lid 11 is provided near its free edge with a pivotally mounted spring-pressed finger 23, rotatably mounted thereon. A leaf spring 24, secured at one end to the inner face of the lid 11, engages at its other end the finger 23 so as to tend to rotate the finger 23 in a clock-wise direction, as seen in Fig. 2. In the closed position of the lid, as illustrated in Fig. 2, such clock-wise movement of the finger 23 is effectively prevented by abutment of the finger on the inner surface of the lid. The finger 23 is also arranged to engage the escapement of a bell crank lever 25. The bell crank lever 25 is pivoted as at 26 to the casing 10. The other end of the bell crank lever is provided with a catch for engaging the lug 27 secured to the free end of a second hinged cover 28, serving as a lid for the lighting compartment of the device. A leaf spring 29 is provided, tending to rotate the bell-crank lever 25 in a clock-wise direction, as seen in Fig. 2.

For automatically opening the lighting compartment cover 28, there is provided a pair of spaced springs 30, each having one end secured to the casing 10 and having its other end in contact with the inner face of the cover 28. These springs exert a pressure against the cover 28, tending to open the cover. The cover is provided with a bracket 32 to which is pivoted an arm 33, having its free end in the shape of a hook. The arm 33 is engaged by one end of a spring 34, the other end of

which is secured to the inner face of the cover 28.

Rotatably mounted within the casing 10 is a toothed wheel 35, having a plurality of pins such as 36, positioned on one lateral face in spaced relation and arranged to be successively engaged by the hook-shaped pivoted element 33. The periphery of the wheel 35 is provided with a plurality of teeth, which are in scraping contact with the surface of a flint 37. The flint 37 is held in intimate contact with the teeth of the wheel 35 by means of a spring 38, mounted within a recessed boss 40 within the casing. A fuel tank 41 is positioned within the lighting compartment and is provided with a gooseneck tube 42 within which is a wick 43. A cover or cap 44 is mounted on the inner face of the lid 28 in such position that when the lid is closed the cap 44 covers the wick 43 and effectively extinguishes the flame.

In operation, assuming that the fuel tank 41 has been supplied with a quantity of fuel, such as benzine or the like, and that cigarettes have been placed within the storage compartment 22, the casing can be carried in the pocket or pocketbook without danger. When it is desired to light a cigarette the button 16 is depressed and the cover 11 automatically opens under the action of the springs 12. As the lid swings open, the finger 23 carried thereby will be rotated in a counter-clockwise direction, as seen in Fig. 2, thus disengaging itself from the bell-crank lever 25. This action will not rotate the lever 25, which will continue to engage at its other end the lug 27, thus holding the cover 28 closed.

After one or more cigarettes have been removed, the lid 11 is closed and the finger 23 then engages the curved end of the bell-crank lever 25, thereby rotating it about its pivot 26 in a counter-clockwise direction. This releases the lug 27 and allows the cover 28 to swing open under the action of the springs 30. As it does so, the hooked end of the arm 33 engages one of the pins 36 thereby rotating the toothed wheel 35 through a part of a revolution in counter-clockwise direction, as seen in Figs. 1 and 4. As it does so, the teeth scrape the flint 37 and cause sparks to be produced, which strike the adjacent wick 43, thus igniting it. The wick 43 is supplied with fuel from within the tank 41.

After the cigarette is lighted from the burning wick, the cover 28 is closed and the cap 44 extinguishes the flame. The cover 28 will be locked in closed position by the lug 27 engaging the bell-crank lever 25, the latter having been returned to its initial position, as shown in Fig. 2, under the control of the leaf spring 29.

The invention upon which this application is based is broader than the specific embodiment shown and described for the purpose of

illustrating at least one of the ways in which it may be employed. The scope of the invention is therefore to be understood as not being limited by the present specific description. I intend no limitations other than those imposed by the claims.

What is claimed is:

1. A cigarette device comprising in combination a casing having a hinged lid, a spring for automatically opening the lid, a latch for locking the lid in closed position, a button for releasing the latch, a second hinged cover, a spring for automatically opening said last-named cover, a bell crank lever pivotally mounted on the casing, a spring-pressed finger on the first-named lid engaging one end of said bell-crank lever, a lug secured to the free end of said last-named cover and engaged by the other end of said bell crank lever, a hook shaped element pivotally secured to said last-named cover and actuated by movement thereof, a toothed wheel having spaced pins selectively engaged by the hook of said pivoted element, said wheel being rotatably mounted on the casing, a flint mounted on the casing and engaged by the teeth of said wheel, a lighting wick adjacent said flint, and a cap carried by the last-named cover for covering the wick in the closed position of the cover.

2. A cigarette device comprising in combination a container for cigarettes and a lighting device, each having a hinged cover, and means for automatically opening the cover of the lighting device when the container cover is closed.

3. In a cigarette device a casing having two independently movable covers, a lighting device automatically operated by the opening of one of said covers and means actuated by the closing of the other of said covers for opening the first-named cover.

4. A cigarette device comprising in combination a container for cigarettes and a lighting device, each having a hinged cover and means for automatically opening one cover when the other cover is closed.

5. In cigarette device a casing having two independently movable covers, a lighting device automatically operated by movement of one of said covers, and means actuated by the moving of the other of said covers for moving the first-named cover.

6. A cigarette device comprising in combination a casing having a hinged lid, yielding means tending to open the lid, manually operable means for maintaining the lid in closed position, a second hinged cover, yielding means tending to open said last-named cover, a bell crank lever pivotally mounted on the casing and having one of its ends engaged by the first-named lid, a lug secured to the free end of the last-named cover engaged by the other end of the bell crank lever, and

friction lighting means actuated by movement of said last-named cover.

7. A cigarette device comprising in combination a two part casing forming a storage compartment and a lighting compartment, said storage compartment having a hinged lid, a spring for automatically opening the lid, a latch for locking the lid in closed position, a button for releasing the latch, a hinged lid for the lighting compartment, a spring for automatically opening said lighting compartment lid, a bell crank lever pivotally mounted on the casing, a spring pressed cam on the storage lid engaging one end of said bell crank lever, a lug secured to the free end of said lighting compartment lid engaged by the other end of said bell crank lever, a hook shaped element pivotally secured to the lighting compartment lid and actuated by movement thereof, a toothed wheel rotatably mounted on the casing, and having spaced pins selectively engaged by the hook of said pivoted element, a flint mounted on the casing and engaged by the teeth of said wheel, a lighting wick, means for pressing the flint into intimate contact with the wheel, and a cap carried by the last-named cover for covering the wick in the closed position of the cover.

30 Signed at Gloucester, in the county of Essex and State of Massachusetts, this 18th day of April, A. D. 1927.
